Weatherford Atty's.

UNITED STATES PATENT OFFICE

2,572,005

MAGAZINE TYPE SAFETY RAZOR

Philip H. Borden, Memphis, Tenn., assignor to
 Central Industrial Corporation, Memphis,
 Tenn., a corporation of Tennessee

Application September 13, 1948, Serial No. 49,017

7 Claims. (Cl. 30—40)

This invention relates to safety razors of magazine type, and particularly to a razor of this type in which the blade is a continuous thin flexible strip preferably having both edges sharpened.

It further relates to a razor of the type in which the blade strip is compactly coiled and is fed from this coil into position for use, and more particularly to a structure of this type in which provision is made for receiving and storing the used blade strip.

It further relates to a razor of this type in which the blade magazine is a replaceable unit which is packaged a roll of blades for use and in which provision is made to receive the used portions of the blade.

It further relates to a magazine for holding the strip coil initially, and for receiving and storing the used portions of the blade, in which the loaded magazine may be attached to the head and other parts of the razor and after exhaustion of the strip be detached; and

It further relates to a safety razor of the replaceable magazine type in which the magazine and used blade therein is removed and thrown away and is replaced by a new unit.

The objects of the invention are:

To provide an improved safety razor of flexible strip blade type;

To provide an improved safety razor of strip blade type having a replaceable blade carrying magazine adapted to receive and store the blade strip as it is used;

To provide a removable blade carrying magazine adapted to store and remove the blade strip for disposal;

To provide a safety razor of magazine type in which a continuous blade strip having sharpened edges is adapted to be fed manually from the magazine into cutting position and the used portions of the strip are concurrently fed back into the magazine for storage;

To provide means for centering the blade within the magazine and against damage to the blade edges as the blade is fed into cutting position;

To provide means for withdrawing the blade from the magazine and advancing it to shift successive portions into cutting position; and

To provide blade retracting means for promoting storage of used portions of the blade strip.

The means by which the foregoing and other objects are accomplished and the manner of their accomplishment will be readily understood from the following specification on reference to the accompanying drawings, in which:

Fig. 1 is a side elevation of the razor with magazine in place and ready for use.

Fig. 2 is a corresponding elevational edge view.

Fig. 3 is an elevational view, partially in section, showing the magazine with used blade strip therein, removed for discard.

Fig. 4 is a similar view of a renewal or replacement magazine and blade unit ready for insertion.

10 Fig. 5 is an enlarged scale, sectional elevation taken on the line V—V of Fig. 6 with the right hand guide sprocket removed.

Fig. 6 is a corresponding sectional elevation taken on the line VII—VII of Fig. 5.

15 Fig. 7 is a plan view of the upper end of the razor.

Fig. 8 is a fragmentary sectional elevation taken on the line VIII—VIII of Fig. 5; and

20 Fig. 9 is a further enlarged fragmentary sectional elevation taken on the line IX—IX of Fig. 10 showing detail of the blade shifting means.

Fig. 10 is a fragmentary sectional plan view taken as on the line X of Fig. 5.

Fig. 11 is a face view of a fragment of the blade strip.

Referring now to the drawings in which the various parts are indicated by numerals:

The razor includes a tape-like strip of thin flexible metal having its opposite edges sharpened 30 to form a long narrow double edge blade 16, which is housed in a hollow body, including a head portion 18 and a handle portion 20, and a complementary magazine 22 which telescopes within the body portion.

35 Initially the blade is housed in a coil 24 within the magazine, unused portions 16A of the blade being successively withdrawn from the coil and fed across the head portion 18 for use, the used portions 16B being concurrently returned into the storage section of the magazine, and there formed into a used coil 24A.

The hollow body 20 is substantially of rectangular cross section with side walls 20A, and edge walls 20B, an is open at its lower end. The upper end or head portion 18 of the body includes a blade support 28 which is arcuately curved in cross section, and extends beyond the cutting edges of the blade 16 and slightly beyond the side walls 20A to form guards 28A. The blade support is provided with longitudinal slots 28B which underlie and expose the cutting edges of the blade 16 for use. The slots in cross section extend downwardly and outwardly and discharge exteriorly to the body below the guards 28A. Immediately adjacent the edge walls 20B the blade

support 28 is cut away, as is shown in the upper right corner of Fig. 5 from which the guide sprocket has been removed, to form slots 20C, and the sprocket chambers 20D. Overlying the blade is a holding member 30 which holds the blade against the blade support 28, the member at its opposite ends curving arcuately downward and connecting into the edge walls 20B.

In the sprocket chambers 20D the support member 28 is provided with bosses 32, which carry shafts 34, and pinions 36 which are centrally disposed between the side walls 20A, the shafts being positioned to project the teeth of the pinions through holes 38 alined along the longitudinal center of the blade strip, and so engaging to aline the blade strip 16 as it leaves the magazine 22, passes across and leaves the head 18.

The blade magazine 22 includes side walls 22A and edge walls 22B, the latter walls being joined at their lower ends by an arcuate continuation 22C which forms the bottom end of the magazine, the upper end of the magazine preferably being closed by a top 22D. Within the magazine an arcuate continuation 22E of the bottom end 22C establishes a chamber 22F for the reception of used blades, the arcuate continuation 22E terminating away from the adjacent edge wall 22B to provide an entrance opening for the used blade 16B. The top 22 of the magazine is provided with openings 22G adjacent the edge walls 22B for the exit of the unused blade portion 16A and the entrance of the used portion 16B of the blade strip. Preferably a guide member 22H restricts deflection of the blade portion 16A between the coil 24 and the opening 22G and a similar guide member, not numbered, may be used adjacent the opposite opening 22G through which the used strip 16B reenters the magazine. The edge walls 22B are provided with longitudinal slots 22J extending upward from approximately the center of coil 24 into adjacency to the top of the magazine for a purpose to be hereinafter disclosed. The side walls 22A carry hubs 40 which journal a shaft 42 on which is mounted a sprocket 44 about which the coil 24 of the blade is formed, the sprocket having projecting teeth which engage the central holes 38 in the blade and prevents its lateral displacement and consequent contact of the blade edges with the sides of the magazine. The side walls of the magazine are also apertured to receive lugs 46 carried by the side walls 20A of the body, which lugs engage and retain the magazine in place in the handle portion of the body.

It will be understood that the walls of the magazine and the body are of light weight metal or plastic and that the side walls 22A of the magazine in the vicinity of the lugs 46 may be inwardly deflected to effect release of latching engagement of the lugs 46 therewith when it is desired to remove the magazine, deflection of the side walls of the handle permitting outward deflection of the lugs during the subsequent removal.

Preferably both edge walls 20B of the handle intermediate their length are outwardly deflected to form channelways 48 which are respectively provided each with a longitudinal slot 48A positioned to aline with a slot 22J of the magazine 22 when the same is in place, the slotted channelways slidably mounting manually operable blade shifters 50 and 52 having toothed portions 50A, 52A, which extend through the slots 22J of the magazine into engagement with the holes 38 of the blade strip portions 16A and 16B respectively. The teeth of the toothed portions 50A, 52A are

of triangular shape and are respectively faced for shifting engagement with the blade holes only during upward movement of the shifter 50 and downward movement of the shifter 52 whereby to concurrently move the blade portion 16A upward toward the head 18 and withdraw the blade portion 16B from the head and feed it into the storage portion of the magazine. Preferably the slots 22J of the magazine and 48A of the channelways are of length to allow proper shifter movement to accomplish a complete cutting sector shift of the blade in the head.

Initially the razor is sold as a unit including the body section and blade equipped magazine section, ready for use.

The shifter 50 is retracted bringing the tooth portion 50A into engagement with the holes in the blade strip and the shifter is subsequently moved upward the length of the slot 22J shifting the blade upward through the opening 22G toward the sprocket 36. The shifter is again retracted, and the operation repeated advancing the blade around the first of the sprockets 36 and across the head until a length of blade has been advanced into cutting position, and preferably into engagement with the second of the sprockets. When after use, the razor requires a fresh section of blade, the shifter is again operated shifting a new cutting length into position in the head and forcing the used portion 16B downward along the edge wall 20B of the body and through the opening 22G into the magazine 22, and thereafter both the shifter 50 and the shifter 52 may be jointly operated, the first to position the blade toward the head and the second to concurrently aid in withdrawing it from the head. Eventually the used portion 16B of the blade is forced downward and into the chamber 22F in which by subsequent advancement the used section is coiled.

It will be understood that in advancing the blade it is usually necessary to advance the cutting edge less than the full length exposed for use, since ordinarily the blade in the central portion of the head does the majority of the work. Under such conditions it is obvious that only such movement of the shifters need be made as is found necessary to accomplish the desired shift.

When the entire strip of blade has been used and the used blade is housed within the magazine the side walls 22A of the magazine are deflected in the vicinity of the lugs 46 to release the lug engagement and the magazine withdrawn, the subsequent outward deflection of the lug carrying portion of the body walls 20A permitting completion of the removal. The magazine removed is thrown away and replaced with a new replacement unit and the operation repeated.

I claim:

1. In a safety razor having a continuous tape-like blade, a hollow body including a handle portion, open at its lower end, said body having at its upper end blade supporting and guarding parts for holding a blade length in cutting position; a replacement magazine externally shaped to conformably telescope within said handle portion, and means to releasably latch said magazine in place; said magazine being adapted to house and journal a coil of said blade and being conformed to receive used portions of said blade; blade shifting means carried by said body for engaging and drawing from said magazine for use successive lengths of blade, for advancing same into said cutting position, and subsequently into said magazine, said body and said magazine being slotted and positioned with said slots in register, and

said shifting means comprising a shifter reciprocably mounted in said registering slots and having a portion extending into engagement with the face of said tape-like blade.

2. In a safety razor having a continuous tape-like blade, a hollow body including a handle portion, open at its lower end, said body having at its upper end blade supporting and guarding parts for holding a blade length in cutting position; a replacement magazine externally shaped to conformably telescope within said handle portion, and means to releasably latch said magazine in place; said magazine being adapted to house and journal a coil of said blade and being conformed to receive used portions of said blade; vertically reciprocable shifting means carried by and extending through one side of said handle portion and a contiguous side of said magazine engaging said tape-like blade for drawing from said magazine for use successive lengths of blade, for advancing same into said cutting position, and subsequently into said magazine, and supplementary vertically reciprocable handle-carried shifting means extending through the opposite sides of said handle and said magazine engaging said tape-like blade beyond said guarding parts for advancing said used portions into said magazine.

3. In a safety razor, a hollow body including blade supporting and guarding parts for receiving and holding successive blade lengths in cutting position, a tape-like elastic blade strip having holes spaced along its longitudinal center, means including a sprocket having teeth engaging holes of said strip establishing and journaling a coil of said strip within said body; vertically reciprocable shifting means carried by and extending through one side of said body for engaging and drawing from said coil for use successive lengths of blade, for advancing same into said cutting position, and subsequently, into said body.

4. In a safety razor, a hollow body including blade supporting and guarding parts for receiving and holding successive blade lengths in cutting position, a tape-like elastic blade strip having holes spaced along its longitudinal center, means including a sprocket having teeth engaging holes of said strip establishing and journaling a coil of said strip within said body; vertically reciprocable shifting means carried by and extending through one side of said body for engaging said strip for drawing from said coil for use successive lengths of blade, for advancing same into said cutting position, and subsequently into said body, and supplementary vertically reciprocable body-carried shifting means extending through the opposite side of said body, engaging said strip beyond said guarding parts for assisting advancement of used portions of said blade into said body.

5. In a continuous blade type safety razor, a hollow body slotted along one side, blade supporting and guarding parts for holding successive blade lengths in cutting position; a blade carrying unit, placed in said body, manually operable shifting means carried by said body, for engaging and removing said blade from said unit, advancing same into said cutting position and subsequently into said unit; said unit comprising a magazine having a side slotted in register with said body slot, a coil of flexible tape-like blade centrally apertured for cooperative engagement with said shifting means disposed within said

magazine, said shifting means being vertically reciprocable in said slots and extending therethrough into said magazine, means carried by said magazine journaling said coil and projecting an end portion thereof upward along said side of said magazine for said cooperative engagement.

6. In a continuous blade type safety razor, a hollow body open at its lower end and having at its upper end blade supporting and guarding parts for holding successive blade lengths in cutting position; a replacement blade carrying unit, means to releasably latch said unit in place in said body, manually operable shifting means carried by said body for engaging and removing successive lengths of said blade from said unit, advancing same into said cutting position and subsequently into said unit; said unit comprising a magazine externally shaped to conformably telescope within said body, said magazine and said body being slotted, said magazine slot registering with said body slot when said magazine is positioned in said body, a coil of flexible tape-like blade centrally apertured for cooperative engagement with said shifting means, said shifting means being mounted in said body slot for vertical reciprocation and extending through said magazine slot when said slots are in register, said coil being disposed within said magazine, means carried by said magazine journaling said coil and projecting an end portion thereof upward along a side of said magazine for said cooperative engagement, and means including sprockets having teeth engaging said blade aperture, to center said blade against lateral displacement, said sprockets including a sprocket forming part of said coil journaling means and additional sprockets journaled within said body in adjacency to opposite ends of said blade supporting and guarding means, said magazine being conformed to receive and house the used said blade.

7. In a continuous blade type safety razor, including a hollow body having at its upper end blade supporting and guarding parts for holding a length of said blade in cutting position, an elongated tape-like blade strip, centrally apertured throughout its length, said strip being coiled and disposed within said body, manually operable shifting means carried by said body for engaging said strip apertures, said shifting means being vertically reciprocable and extending through said body into engagement with said apertures for advancing said strip into said cutting position, and sprockets having teeth engaging said apertures to center said blade against lateral displacement, said sprockets being journaled in said body adjacent the opposite ends of said blade supporting and guarding parts.
